(57) **CLAIM**

The ornamental design for a dermabrasion device housing, as shown.

DESCRIPTION

FIG. 1 is a perspective view of an open dermabrasion device housing with closed interior compartment showing my new design;

FIG. 2 is a perspective view of an open dermabrasion device housing with an open interior compartment;

FIG. 3 is a perspective view of the dermabrasion device housing when closed;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front plan view thereof;

FIG. 9 is a rear plan view thereof;

FIG. 10 is a top plan view of an open dermabrasion device housing, with a closed interior compartment; and,

FIG. 11 is a detail view of a control panel for a dermabrasion device housing.
